C. BAUMAN

LOCOMOTIVE

Filed Nov. 5, 1920

INVENTOR:
Carl Bauman,

UNITED STATES PATENT OFFICE.

CARL BAUMAN, OF PINE ISLAND, MINNESOTA.

LOCOMOTIVE.

Application filed November 5, 1920. Serial No. 422,095.

To all whom it may concern:

Be it known that I, CARL BAUMAN, a citizen of the United States, residing at Pine Island, in the county of Goodhue and State of Minnesota, have invented a new and useful Locomotive, of which the following is a specification:

My invention relates to improvements in locomotives, the primary object being to provide novel means for compressing air in the usual boiler (used as an air container) of a locomotive or other tank, and utilizing the air so compressed for power purposes. A further object is to provide for employing the available wasted energy derived when a locomotive is coasting or drifting.

To these ends my invention comprises the features of construction and combination of parts hereinafter described and claimed.

In the accompanying drawing forming part of this specification, Fig. 1 is a side elevation of a locomotive shown provided with my improvement and Fig. 2 is a front elevation of a locomotive showing my improvement.

In the drawing, A indicates the usual boiler of a locomotive, which is employed not to generate steam, but as a compressed air storage tank in the use of my invention. This tank is charged with compressed air from suitable supply stations along the line of travel, which charges are replenished in travel by an air compressor B which consists of a cylinder 10 secured by the fastenings 11 on portions of the locomotive and of a piston 12 reciprocable in said cylinder. The piston has a piston rod 13 connected to a guide head 14, which is slidably supported between the guides 15 carried by the frame of the cylinder 10. The piston 12 is reciprocated to compress air by means of a rocker arm 16 pivotally connected by a link 17 at one end to the guide head 14 and pivotally connected at its opposite end to the usual guide head 19, which is associated with the usual steam cylinder 20 of the locomotive. A shiftable fulcrum 21 is provided, upon which the rocker arm 16 tilts as the guide head 19 reciprocates to transmit reciprocating motion to the air compressor piston 12 when the locomotive is traveling under power or drifting. The length of stroke of the piston 12 can be varied as de-

sired by changing the position of the fulcrum, said fulcrum being mounted upon an arm 22 which is pivoted at its end opposite the fulcrum 21, as at 23, on a supporting portion of the locomotive. The free end of arm 22 carrying the fulcrum is raised 55 and lowered and held in regulated position by means of the bell crank 24, links 25 and 26, hand lever 27 in the cab 28 of the locomotive and the quadrant 29, with which the lever 27 co-operates in the usual manner. The compressed air cylinder 10 is connected by the duct 30 with the tank A to transmit compressed air supplied by the compressor to the tank, a check valve 31 being interposed in said duct to prevent back action of the compressed air from the locomotive boiler or other air container. The valve housing 32 of the cylinder 20 is also connected with the dome 33 of the locomotive in the usual manner by means of 70 the supply duct 34.

In use, when the locomotive is in motion, the piston 12 is reciprocated, the length of stroke being regulated as desired by the handle 27, the longer the stroke 80 the greater the pressure of air produced by the compressor. This compressed air is forced into the locomotive boiler A or other tank and in turn is available to reciprocate the piston in the cylinder 20 and operate the 85 drive wheels 35 of the locomotive. This action follows when the locomotive is drifting, the motion acting to augment the operating medium contained in the boiler or tank. When the locomotive is being driven, the length of stroke of the piston 12 is shortened by shifting the fulcrum upwardly 90 to reduce the resistance occasioned by the operation of the compressor at such time when the locomotive is propelled by compressed air. When the locomotive is coasting or drifting, the length of the stroke of the piston 12 is lengthened to increase the capacity of the compressor, the increased power required for operating the 95 same under such conditions being acquired from the moving parts then propelled by the momentum of the locomotive.

In accordance with the patent statutes, I have described the principles of operation of my invention, together with the apparatus which I now consider to represent the best embodiment thereof, but I desire to 100

have it understood that the construction shown is only illustrative and that the invention can be carried out by other means and applied to uses other than those above set forth.

Having described my invention, what I claim as new and desire to secure by Letters Patent is:

1. In combination with a locomotive having an air container, a cylinder communicating with said container, a reciprocable driving member in said cylinder propelled by air from said container, an air compressor comprising a cylinder and a piston therein, said cylinder discharging into said container and power transmitting means between said piston and reciprocable member for driving the former.

2. In combination with a locomotive having an air container, a cylinder communicating with said container, a reciprocable driving member in said cylinder propelled by air from said container, an air compressor comprising a cylinder and a piston therein, a conduit leading from said cylinder to said container, a check valve in said conduit to prevent the return of compressed air from the container to the compressor and power transmitting means between said piston and reciprocable member for driving the former.

3. In combination with a locomotive having a cab and a boiler, said boiler serving wholly as an air container, a cylinder having a working piston for driving the locomotive, an air compressor having a cylinder and a piston, a lever movably connected to the working piston and the piston of the air compressor; a fulcrum for said lever movably positioned to vary the length of stroke of said lever and means for shiftably holding said fulcrum, said means extending

to the cab of the locomotive for the purposes specified.

4. In combination with a locomotive having a boiler serving wholly as an air container, a cylinder having an air driven reciprocable member for driving purposes, and means for compressing air, said means being operated by said reciprocable member and connected with said boiler to replenish the supply of air therein.

5. A locomotive including an air container, a cylinder communicating therewith, an air driven piston in said cylinder for driving the traction wheels of the locomotive and an air compressor emptying into said container, said compressor including a working member coupled to said piston and operated thereby.

6. In a device of the class described, a locomotive having a cylinder and a working piston therein for driving the locomotive, an air compressor, means driven from said piston for operating said compressor, and means accessible from the cab of the locomotive to affect said compressor driving means, whereby more or less power is taken from the piston.

7. A locomotive including an air container, a cylinder communicating therewith, an air driven piston in said cylinder for driving the traction wheels of the locomotive, an air compressor emptying into said container, said compressor including a working member and variable power transmitting means between said piston and working member for increasing or diminishing the action of the latter with the consequent consumption of more or less power from the former.

In testimony whereof, I have signed my name to this specification.

CARL BAUMAN.
